UNITED STATES PATENT OFFICE.

HENRY ELLEAU, OF SAN FRANCISCO, CALIFORNIA.

DESIGN FOR A BADGE.

SPECIFICATION forming part of Design No. 16,544, dated February 23, 1886.

Application filed October 29, 1885. Serial No. 181,337. Term of patent 3½ years.

To all whom it may concern:

Be it known that I, HENRY ELLEAU, a citizen of the United States, residing at the city and county of San Francisco, and State of California, have invented and produced a new and original Design for Badges, of which the following is a specification, reference being had to the accompanying drawings, forming part thereof.

Figure 1 is a front view of the badge. Fig. 2 is a view showing the reverse side of the pendant or star-shaped portion.

The object of my invention is to produce a new and original design for badges; and to this end the same consists in a design showing a flat ribbon-like body having at its upper extremity the figure of a bear represented as standing upon a bar, and at its lower extremity a pendant of the ordinary five-pointed-star shape.

In the drawings the ribbon and pendant are represented at B and C, respectively, and the bear at D, mounted upon a bar, A, in such a manner as to appear integral therewith, the parts being arranged substantially in the manner shown in the drawings. 25

Having described my new design for a badge, I claim—

The design for a badge, consisting of the figure of a bear, D, bar A, ribbon B, and star-shaped pendant C, substantially as described. 30

In witness whereof I have hereunto set my hand.

HENRY ELLEAU.
